United States Patent Office.

SAMUEL MARDEN, OF NEWTON MASSACHUSETTS, ASSIGNOR TO HIMSELF AND DUSTIN LANCEY, OF SAME PLACE.

Letters Patent No. 60,918, dated January 1, 1867.

IMPROVED PEAT MACHINE.

The Schedule referred to in these Letters Patent and making part of the same.

TO ALL WHOM IT MAY CONCERN:

Be it known that I, SAMUEL MARDEN, of Newton, in the county of Middlesex, and State of Massachusetts, have invented a new and improved Peat Machine; and I do hereby declare that the following is a full and exact description thereof, reference being had to the accompanying drawings, and to the letters of reference marked thereon, making a part of this specification, of which—

Figure 1 is a vertical section through the hopper and perforated table of the machine.

Figure 2 is a top view or plan of ditto.

Figure 3 is a vertical section through the mould carrier.

Figure 4 is a side elevation of the machine.

Figure 5 is a view of the top of the mould carrier.

Figure 6 is a view of the top of the revolving beater.

Figure 7 is an end elevation of the revolving beater.

A represents the flexible perforated apron or table. B the revolving beater. C the hopper or box of machine, a' its open cover, and a its sieve, b its inclined bottom, c its pointed guide or chute. D the driving shaft; d cam for actuating sieve arm e; f worm on shaft D to engage with and drive the worm gear g on upright hollow shaft h of revolving circular mould carrier E; i i i, &c., radial grooves of mould carrier, and k k k, &c., its spring abutments; l its cam for actuating the sliding moulds m m m, &c.; n the guard for compressing the peat; o the knife for cleaning the outer surface of the mould carrier; p p the spiral springs of the moulds.

There is a great variety of peat machines, but all aim at the same result, namely, to prepare peat for market in the quickest and best possible shape. The reason why so many machines fail, and are comparatively useless, is because of their complexity in structure, and consequently the expense in making and running them, and liability to get out of order. My machine is simple in structure, and easily repaired when out of order, cheap, performs its work rapidly, and leaves the product in merchantable order.

To enable others skilled in the art to make and use my invention, I will proceed to describe its construction and operation.

1. As to its construction. By referring to the accompanying drawings, a very correct idea may be had of its several parts. A represents a flexible apron or table into and upon which peat from the bog is thrown. It is double and perforated, the space between being filled with some porous substance, through which water may escape while the solid is retained, but I may use any perforated or proper material in its place. B is the revolving beater. (See drawings, figs. 1, 6, and 7.) It consists of a drum made of brass, or other suitable material, and firmly attached to the driving shaft. This drum has firmly set in it, longitudinally and at different angles, strips of steel projecting, say, quarter of an inch from the drum. These strips are notched, but arranged consecutively in different directions, like saw teeth. The number of strips, the angles at which they are set, and the fineness of the teeth may vary, but the object is to tear to pieces and reduce to fineness or to a paste the crude peat. I may use, however, iron or other metal suitable for the purpose for the teeth. The driving shaft D is made of iron or steel, at one end of which is applied the power propelling the machine, and at the other end is the worm f, which engages and drives the gear attached to the upright shaft h. (See fig. 2, in drawings.) This shaft has also upon it, near the propelling power, a cam, d; its use is, when the shaft revolves, to operate on the sieve arm e in such a manner as to shake the sieve. (See figs. 2 and 7 in drawings.) The driving shaft carrying the beater is placed over the bend of the apron and rests upon the frame of the machine. (See figs. 1, 2, and 4 in drawings.) Over the beater is a cover of sheet metal—other material may be used—screwed or fastened upon the open wooden frame a'; this frame is hung upon hinges, and may be opened when necessary. The sieve a is a common coarse sieve, through which the reduced peat falls into the hopper C. This hopper, made of wood, and of any desirable size, has an inclined bottom b, (see fig. 3 in drawings,) its lowest inclination being on a level with the radial grooves of the mould carrier; it has also a pointed guide or chute c. (See figs. 1 and 3.) The inclined bottom and chute are for the purpose of conducting more readily and without clogging the reduced peat into the radial grooves. h is the upright revolving shaft. (See figs. 3 and 4.) On its upper end is the gear connected with the worm gear on the driving shaft. When the machine is operated by steam power the shaft is designed to be hollow for the purpose of allowing steam to circulate in it, as, also, steam may be introduced and circulate in the moulds, grooves, and open spaces in the mould carrier for the purpose of keeping the machinery warm, causing it to work more easily. Next the gear also is a clamp or guide surrounding the shaft and made fast to the frame of the machine to keep it steady and in place; the lower end of the shaft is fastened to a plate screwed to the spring abutments, k k, &c., and the plate has also a socket projecting upward, into which the shaft passes and is thus made more secure, being firmly soldered. The lower end of the shaft also slips on to a pin or pivot projecting into the shaft, say an inch or more, which pin or pivot passes through the

cam *b* and is firmly fastened to the bottom of the machine. This pivot has also two shoulders, the upper made square. (See drawings, fig. 5.) This shaft and pivot are made of iron or steel. The cam, *b*, is for actuating the sliding moulds; it is immovable, kept in place by the square upper shoulder of the pivot, the lower shoulder of the pivot, on which it partially rests, the frame of the circular mould, and the plate above, which is fastened to the shaft; it is elliptical in form, or nearly so, with an elevation on the side nearest the guard, or what nearly resembles a segment cut from the side thereof, the point of cutting—moving from right to left—being in line, or nearly so, with the centre of the pivot and the left extremity of the guard *n*. This form of the cam will be explained hereafter. The sliding moulds, *m m*, &c., are made square at the outer extremity and rounded at the other end, always pressing more or less against the cam; they slide back and forth in the radial grooves, *i i*, &c., pushed by the spiral springs *p p*, &c.; they are also kept in place partially by the fixed spring abutments *k k*, &c. (See fig. 5 in drawings.) *n* is the guard for compressing the peat; it is made in the form of the segment of a circle; it is fastened to the bottom of the frame of the machine, covering the side and partially the top of the circular mould carrier, and extending say nearly one-third of the perimeter of the circular mould carrier, as seen at fig. 2 in drawings. The revolving circular mould carrier, *E*, is well represented by the figs. 5 and 2 in drawings; it is moved by the upright shaft, revolving also about the pivot before described; it is made of brass, as also is the cam *b*, the sliding moulds, the guard, and the spiral springs, and the spring abutments, which are a part of the mould carrier; but I do not confine myself to the use of brass, but may use other metals. The number of moulds of course varies with the size of the machine. The use of the knife, *O*, is simply to clean or keep clear the circular mould.

Having thus described the structure of the machine, I will now explain its mode of operation. The peat is taken in its crude state and thrown in and upon the apron, where it comes under the teeth of the revolving beater, which tears or grinds the mass into a paste, and in the revolution the ground peat is thrown or falls upon the sieve, being also prevented from passing over the drum by a slide or knife extending the length of beater and sliding down to the teeth. The motion of the sieve causes it to fall through into the hopper, and being moist, and the bottom of the hopper being inclined, the peat readily falls into and fills the radial grooves, as, in the revolution of the circular mould carrier, the grooves pass under the hopper. It will be seen by examining fig. 3 of the drawings that the shape of the cam is such that when the radial grooves come under the hopper the sliding moulds are farthest withdrawn from the outer rim of the mould carrier by the action of the spiral springs; so when the grooves, filled with peat from the hopper, go under the guard, *n*, the pressure of the ends of the moulds begins against the peat enclosed in the grooves between the end of the grooves and the side of the guard. This pressure increases while the grooves are under the guard, compressing the peat, of course, into a small space, and somewhat into the shape of a brick. As the grooves pass out from under the guard, the sliding moulds still pressing harder against the peat, the peat, of course, would crumble and break but for the peculiar shape of the cam *b*. As the end of the sliding mould passes the elevation or the point where the segment is cut off, the mould slides the width of its outer end without pressure, which allows the whole mass to be pressed equally upon when the pressure begins again, so that the mass is pressed and falls off unbroken before it reaches the knife, and thus the work is completed.

The great advantage gained by my machine over others now in use is its simplicity in construction, and consequently the cost of making will be much less than any other now in use. The machine is easily repaired when out of order, and, having but few levers and joints, it is little likely to get out of order. It is, therefore, a cheap machine; it is also novel, operating in a manner unlike any now in use; leaves its product in good, marketable shape, and is, therefore, of practical advantage to the public.

I am aware that the United States issued Letters Patent to E. H. Ashcroft, of Lynn, Massachusetts, of date April 24, 1866, for an improvement in peat machines, in which was a revolving cylinder with pins set in it for breaking up peat, with appliances for draining connected therewith. I disclaim his invention. I am aware, also, that Letters Patent of the United States were issued to C. Marsh, of date July 24, 1860, for a cracker machine. I disclaim his invention.

What I claim as my invention, and desire to secure by Letters Patent, is—

- I claim the tearing apparatus, composed of metallic plates, notched in the manner of saw-plates, set and arranged at different angles in the drum-beater *B*, in combination with the flexible apron *A*.
- I claim the vibrating sieve operated upon by the cam *d*, as applied to or in combination with peat machines, substantially as described.
- I claim the cam *d*, arranged and operating upon the sieve arm *e*, so as to sift the reduced peat, substantially as described.
- I claim the cam *b*, so constructed and arranged, with respect to the sliding moulds *m m*, &c., and the guard *n*, that the pressure on the guard by the sliding moulds ceases for a space equal to the width of the sliding moulds as they emerge from the guard.
- I claim the circular mould carrier *E*, revolving about the fixed cam *b*, as combined and arranged with the compressing guard *n*, it being also provided with radial grooves *i i*, &c., converging toward its centre and supporting sliding moulds *m m*, &c., operated upon by the cam *b* and the spiral springs *p p*, &c., which keep the sliding moulds in proximity to the cam, all combined and arranged for the purpose of compressing peat, and as applied to peat machines, substantially as described.
